UNITED STATES PATENT OFFICE.

ROBERT GILMORE CAMPBELL, OF GREENSBORO, NORTH CAROLINA, ASSIGNOR OF ONE-HALF
TO CEASAR CONE, OF GREENSBORO, NORTH CAROLINA.

GUIDE FOR WARP-WINDING MACHINES.

No. 890,213.

Specification of Letters Patent.

Patented June 9, 1908.

Application filed January 9, 1907. Serial No. 351,469.

To all whom it may concern:

Be it known that I, ROBERT GILMORE CAMPBELL, a citizen of the United States, residing at Greensboro, in the county of Guilford and State of North Carolina, have invented certain new and useful Improvements in Guides for Warp-Winding Machines; and I do hereby declare the following to be a full, clear, and exact description 10 of the invention, such as will enable others skilled in the art to which it appertains to make and use the same.

My invention relates to warp winding machines, has especial reference to the traverse 15 arm traveling alternately across the machine from one side to the other to guide the warp as it is being wound upon a spool or ball, and the invention consists in certain improvements in guides on the arms of the 20 traverse which will be fully disclosed in the following specification and claims.

As heretofore constructed, the arms of the traverse have been provided with conical tubular or trumpet like guides, through which 25 the warp travels, and the warp in traveling through the guides is subject to a deteriorating effect due to friction, which frequently breaks the fiber of the warp and makes it rough and ragged. It is my purpose to overcome this serious defect, and 30 deliver the warp to the spool or ball in the condition in which it came from the spinning machine.

In the accompanying drawings, which 35 form part of this specification:—Figure 1 represents a side elevation partly in section of the traverse for guiding warp to a winding machine. Fig. 2 an end view of the same, partly in section. Fig. 3 an elevation of one 40 of the guides on an enlarged scale, and showing the arm of the traverse in section. Fig. 4 a top plan view of one of the arms of the traverse detached and Fig. 5 a top plan of the vertical warp guides.

Reference being had to the drawings and the designating characters thereon, the numeral 1 indicates the shaft of the traverse, provided with opposite spiral grooves 2, 3, respectively, and the shaft is supported at 45 its ends in suitable bearings, not shown, and

is revolved or driven by the means usually employed in such machines.

On the shaft 1 is a traverse or carriage 4, having a vertical arm 5 on opposite sides of which are horizontal guide rolls 6, between 55 which the warp 7 travels, and loops 8 which prevent the warp jumping off the rolls.

8' are guide sheaves supported on arm 9, secured to arm 5, and the sheaves are arranged at a right angle to the rolls 6 and direct the warp to guides on the ends of the arms 10 of the traverse. The guides consist of vertical rolls 11, in front and adjacent to which is a transverse loop 12 to prevent the warp rising on the rolls, and a transverse bar 65 13, on which the warp may rest in its passage from the sheaves 8'. The upper surface of the bar 13 is rounded to prevent abrasion, tearing or breaking the fiber of the warp as it travels over the bar. The rolls 11 are secured to the arms 10 by bolts 14 and revolve 70 freely thereon, propelled by frictional contact of the warp, without injuring the fiber of the warp, and the arms 10 may be secured to the traverse or carriage by screws 15. 75

The traverse or carriage 4 is connected to the spirally grooved shaft 1 by a spanner 16, provided with opposite extensions 17 which engage the grooves 2, 3, and the traverse is prevented from turning on the shaft 1, by an 80 arm 18 having a bifurcated end 19 which engages a transverse rod 20 between the sides of the frame of the winding machine, not shown. As the warp 7 proceeds from a spinning machine, the traverse feeds it to the 85 spool on which it is wound, by the guide rolls on the ends of the arms of the traverse without the rupture of its fiber, and thereby preserves the warp in its original condition.

Having thus fully described my invention, 90 what I claim is

In a warp winding machine, an oppositely spirally grooved shaft, a fixed rod a laterally movable transverse carriage connected to said shaft, and having an arm extending 95 therefrom and engaging the fixed rod to prevent the carriage turning on the shaft, a vertical arm extending from the carriage having horizontal guide rolls on opposite sides of the arm and loops above the rolls, a horizontal 100

arm secured to said vertical arm below said
guide rolls and having sheaves thereon on op-
posite sides of the vertical arm, and horizon-
tal arms extending laterally from the carriage
5 on opposite sides thereof and provided at
their ends with vertical guide rolls opposite
each other.

In testimony whereof I affix my signature
in presence of two witnesses.

ROBERT GILMORE CAMPBELL.
